Nathaniel Frucht, Providence, R. I.

Application March 10, 1938, Serial No. 195,022

12 Claims. (Cl. 281—29)

My present invention relates to the manufacture of books and the like, and has specific reference to a novel construction for binding pages and leaves secured with spiral wire coils, to a cover.

It is the principal object of my invention to provide a simple and inexpensive construction for locking the spiral wire coil to a cover.

A further object of my invention is to provide a construction which permits structurally flat opening of the book at any point.

Another object of my invention is to provide a construction which will hold each coil of wire under a slight tension so as to render the mounting more rigid.

With the above and other objects and advantageous features in view, my invention consists of a novel arrangement of parts more fully disclosed in the detailed description following, in conjunction with the accompanying drawings, and more specifically defined in the claims appended thereto.

In the drawings:

Fig. 1 is a perspective view showing the novel mounting of pages;

Fig. 2 is an enlarged detailed section showing the relative positions of the wire coil and the novel lock arrangement therefor;

Fig. 3 is an end section of Fig. 2 on the line 3—3 of Fig. 2;

Fig. 4 is a section on the line 4—4 of Fig. 2;

Fig. 5 is a perspective view of the novel lock base;

Fig. 6 is a detailed view similar to Fig. 4, showing how the end of the wire is turned for locking in place;

Fig. 7 is a view showing a different slot construction for the lock base;

Fig. 8 is a perspective view showing a lock base with a combination of slots such as shown in Fig. 5 with end slots such as shown in Fig. 7;

Fig. 9 is a perspective view of a modified construction of a lock base suitable for small note book fillers; and

Figs. 10, 11 and 12 are perspective views respectively of a modified lock base and a retainer member therefor, designed for permitting replacement of new pages in a cover.

It has been found desirable to provide a locking arrangement for check books, blank books, printed pages, and the like which are secured together and supported by means of a spiral wire coil. The preferred locking arrangement consists of a lock base for effectively gripping the separate wire coils, the lock base then being se-

cured to a cover. I have provided a lock base which may be made in one piece out of sheet metal stock, preferably by stamping, and which will engage each separate coil of the spiral wire and will effectively hold it under slight tension, thus increasing the rigidity of mounting of the pages within a cover, the novel lock base being designed to extend upwardly within the spiral coil and to generally conform to the shape of the coil itself so as to provide a firm base for the inner ends of the pages or leaves. Although the novel lock base is primarily designed for permanent mounting to a cover, the construction may be modified to permit removable mounting and thus provide for refills of replacement pages.

Referring to the drawings, a book 10 is illustrated having a plurality of leaves or pages 11 secured together by means of a spiral wire coil 12, the spiral wire coil being locked to an outer cover 13 by means of a novel lock base 14. The leaves are freely movable on the wire coil 12, see Fig. 2, as each leaf is provided with a plurality of openings 15 of larger diameter than the width of the wire forming the spiral coil, which is threaded through the openings in well known manner. The novel lock base 14, see Fig. 5, is preferably stamped from sheet metal into an arcuate generally U-shaped form, with a plurality of slots 16 on each edge 17, the stock being shaped and bent over at the ends to form closures 18 which terminate in outwardly extending tabs 19 having openings 20 therethrough to permit riveting of the tabs to the book cover. The height of the slots is preferably slightly less than the normal height of the wire coil above the back of the cover, whereby the base of each coil is slightly flattened to impart a desirable tension to each separate coil and thus increase rigidity of the mounting. Each slot is preferably slightly widened at the entrance to facilitate positioning the wire coils within the slots, the assembly being made by inserting the lock base through the coil, positioning the separate wire coils in their respective slots, and then riveting the tabs 19 to the back of the cover. The ends 21 of the coil are gripped by the end slots, and need not be locked therein for ordinary book construction, but may be turned laterally if desired as indicated in Fig. 6, to provide a permanent lock of the free ends of the spiral coil within the lock base. If the book pages have substantial width, there may be a slight tendency for the cover to bow outwardly and thus leave a slight gap adjacent the center of the mounting; in such case, I may make the edges of the lock base convex to compensate

for such bowing, or I may form the lock base with two tabs which extend laterally from the edges adjacent the center of the lock base for additional riveting to the cover.

5. Although I have described a simple and satisfactory construction which utilizes a single easily manufactured locking element, the construction of the parts may be modified to secure a better locking, Fig. 7 showing an illustrative keyhole construction of slot 22 with inwardly sloping sides which form a restricted entrance to a slightly enlarged wire receiving recess 23, thus permitting a snap passage of the spiral wire coils into the terminal recesses 23, whereby the coils 10 cannot be inadvertently displaced or separated from their respective slots. Or, the slots may be a combination of the type indicated at 16 with end slots of the keyhole type indicated in Fig. 7, as shown in Fig. 8, the end slots then gripping the free ends of the coil so as to obviate necessity for turning the free ends laterally within the lock base as illustrated in Fig. 6.

For small pocket refills, such as for example for pocket check books, the lock base may be 25 formed as illustrated at 24 in Fig. 9, the ends 25 being provided with downwardly extending fingers 26 which may be bent inwardly as indicated in dotted lines to detachably lock the movable lock base and its associated pages to a cover, 30 the preferred construction including recesses within the cover into which the bent tongues may be received. If the cover is made of flexible material, the fingers 26 may be initially bent, and the cover then curved so as to slip the bent 35 fingers into the receiving cover recesses.

If it be desired to provide a refill arrangement, the novel lock base may be formed as indicated at 27, in Fig. 10, with downwardly extending fingers 27a which are inserted in openings 28a 40 in a slider plate 28 and bent over, the slider plate closing the open ends of the slots and being adapted to be slidably received within a retention member 29 having inturned edges 30; the lock base 27 and its associated pages and spiral 45 coil can be detachably secured to the cover by sliding the plate 28 within the edges 30, suitable releasable locking means such as snap projections and for retaining the parts together being provided if desired. In certain constructions, it 50 may be preferred to form the slider plate 28 of relatively flexible material, so that the mounting within the member 29 may be accomplished by simply bending the sides of the lock base towards each other and positioning the flanges 55 within the member 29, then releasing the lock base to permit the flanges to slide laterally into locking engagement within the edges 30.

While I have described specific constructional embodiments of my invention, it is obvious that 60 changes in the construction of the parts, in the materials used therefor, and in the general arrangement of the slots and the cover securing means for the locking base, may be made to suit the requirements for different book designs, 65 without departing from the spirit and the scope of the invention as defined in the appended claims.

I claim:

1. In combination, with a coil support for a 70 book or the like, a lock base having a central portion and spaced sides with aligned free edges, the free edges of said sides having slots to receive the coils of said support, and a closure secured to said base and closing said slots to lock the coils 75 in the slots.

2. In combination with a coil support for a book or the like, a cover, a lock base having a central portion and spaced sides with aligned free edges, the free edges of said sides having slots to receive the coils of said support, and means securing said base to said cover with said edges engaging said cover to lock the coils in the slots. 5

3. In combination with a coil support for a book or the like, a cover, a lock base having a central portion and spaced sides with aligned free edges, the free edges of said sides having slots to receive the coils of said support, and means for securing said base to said cover with said edges engaging said cover to lock the coils 15 in the slots, said means including tabs secured to said cover.

4. In combination with a coil support for a book or the like, a lock base having a central portion and spaced sides with aligned free edges, the free edges of said sides having slots to receive the coils of said support, said lock base having closed ends, and a closure secured to said base and closing said slots to lock the coils in the slots. 20

25 5. In combination with a coil support for a book or the like, a cover, a lock base having spaced sides, the edges of said sides having slots to receive the coils of said support, said lock base having closed ends terminating in tabs secured to said cover, whereby the edges engage the cover to lock the coils in the slots.

30 6. In combination with a coil support for a book or the like, a cover, a lock base having spaced sides, the edges of said sides having slots to receive the coils of said support, said lock base having closed ends terminating in finger tabs secured to said cover, whereby the edges engage the cover to lock the coils in the slots. 35

7. In combination with a coil support for a book or the like, a lock base having spaced sides, the edges of said sides having slots to receive the coils of said support, said slots having recesses shaped to firmly grip said coils, and a closure secured to said base and closing said 45 slots to lock the coils in the slots.

8. In combination with a coil support for a book or the like, a lock base having spaced sides, the edges of said sides having slots to receive the coils of said support, the end slots having recesses shaped to firmly grip said coils, and a closure secured to said base and closing said 50 slots to lock the coils in the slots.

9. In combination with a coil support for a book or the like, a cover, a retention member having flanged edges and secured to said cover, and a lock member having a central portion and spaced sides terminating in aligned edges, said edges having spaced transverse edge slots adapted to receive individual coils of the coil support, 60 and said lock member having lateral portions extending outwardly from said sides and adapted to slide within the flanged edges of the retention member. 55

10. In combination with a coil support for a book or the like, a cover, a lock base having a central portion and spaced sides terminating in aligned free edges, the free edges having spaced slots for receiving individual coils of said support, a closure member for closing the open ends 70 of said slots to lock the individual coils therein, and means for securing the closure member to said cover. 65

11. A lock base for a book cover comprising an elongated straight sheet metal member of 75

inverted U-shape in transverse cross section, the edges of the sides having spaced slots adapted to receive a coiled leaf support, said base having at each end an integral portion forming a closure, said closure portion having an integral angularly directed lock tab.

12. A lock base for a book cover comprising an elongated straight sheet metal member of

inverted U-shape in transverse cross section, the edges of the sides having spaced slots adapted to receive a coiled leaf support, said base having at each end an integral portion forming a closure, said closure portion having an integral lock tab.

NATHANIEL FRUCHT.
